S. ATVS

UNITED STATES PATENT OFFICE.

WILLIAM H. RIPLEY, OF BLOOMFIELD, NEW JERSEY, ASSIGNOR TO THE PROMETHEUS ELECTRIC COMPANY, A CORPORATION OF NEW YORK.

ELECTRIC HEATING APPARATUS.

No. 893,015.

Specification of Letters Patent.

Patented July 14, 1908.

Application filed October 5, 1906. Serial No. 337,594.

To all whom it may concern:

Be it known that I, WILLIAM H. RIPLEY, a citizen of the United States, residing at Bloomfield, in the county of Essex and State of New Jersey, have invented certain new and useful Improvements in Electric Heating Apparatus, of which the following is a specification.

My invention relates to improvements in electric heating apparatus having particular reference to devices for warming plates, dishes and similar articles in ovens, air tight closets and like receptacles and comprises a device to be operated and controlled by the application of direct, alternating, or intermittent electric currents to a suitable resistance and the passage of air currents therethrough or thereover.

In the following is described in connection with the accompanying drawings an embodiment of the invention utilizing a direct current, the features thereof being more particularly pointed out hereinafter in the claims.

In the drawings Figure 1 is a longitudinal sectional view of an air tight receptacle illustrating the heating device as mounted in a separate compartment; Fig. 2 is a longitudinal sectional view illustrating a modified form of the heating device as applied to one of the walls or casing of an air tight receptacle; Fig. 3 is a longitudinal sectional view illustrating a modified form of the heating device supported within an air tight receptacle or compartment at a distance from the walls; and Fig. 4 is a vertical sectional view on the line A—B of Fig. 3.

Similar numerals of reference indicate similar parts throughout the several views.

1 indicates an air tight receptacle or compartment comprising an end wall 2, side, top and bottom walls 3, and a door 4 attached to one of the side walls 3 by means of hinges 5. 6 is an auxiliary wall mounted in said receptacle at the rear end thereof and has suitably formed therein air inlet holes 7, and outlet holes 8, said auxiliary wall 6 and end wall 2 forming supporting means for the bottom plate 9 and deflecting plate 10 of the heating device 11.

12 are a series of current carrying and heat generating electrical resistances suitably mounted on insulating studs or blocks 13 fastened to the inner face of end wall 2, the uppermost of said resistances being in con-

tact with the main or electric lead wire 14 and the lowermost in contact with return wire 15, the intermediate portions thereof being adapted to be connected in series by means of wire connections 16.

As illustrated in Fig. 1 of the drawings E indicates the manner in which the plates and dishes are placed in a receptacle or compartment, the arrows indicating the direction in which the air is forced during the heating of the same.

Referring to Fig. 2 of the drawings 17 indicates a heating device rigidly fastened to the inner face of end wall 2, said heating device comprising front and side walls 18, a bottom 19, in which are air inlet holes 20, and an air outlet means comprising a screen mesh 21 suitably mounted on the top of front, end and side walls 18, the heated air following the course as indicated by the arrows. The resistances and means for supporting the same in said air tight receptacle or compartment are as described above.

Referring to Fig. 3 the heating device comprises side walls 22, front and back walls 23 and bottom 24, said front and bottom walls having formed therein air inlet means 25; the air outlet means comprises a screen mesh 26; the device together with the resistances and means for supporting the same are held in position within the air tight receptacle or compartment 1 by means of bracket arms 27.

The electric wiring as shown in Fig. 4 of the drawings illustrates the application of multiple winding, while that shown in Fig. 1 illustrates the same device wound in series.

The operation of the device is as follows:—Plates, dishes, and articles of that nature may be placed within the air tight receptacle or compartment 1 and the door 4 closed. Current is then permitted to pass from electric main 14 through resistances 12 causing the same to become heated to as high degree of heat as is desirable, the current being controllable by any suitable means (not shown). The air in said receptacle enters the heating device through the inlet holes, passes over the resistances and circulates in a current in the direction indicated by the arrows.

It is obvious that varied degrees of heat may be obtained by regulating the amount of current used, and that the same may be controlled and the distribution of heat equalized by the means described. It is fur-

ther obvious that the means for accomplishing the above may be widely varied without departing from the spirit of the invention.

What I claim and desire to secure by Letters Patent of the United States is:—

1. A device of the character described comprising a closed chamber, an auxiliary housing formed therein, a heating device mounted in said housing, and means adapted to permit the circulation of air from said chamber through said housing.

2. A device of the character described including a closed chamber, an auxiliary compartment mounted in the casing of said chamber, a heating device comprising a plurality of electrical resistances mounted in said auxiliary compartment, and means adapted to permit the circulation of air from

said chamber through said auxiliary compartment.

3. A device of the character described including a closed chamber, means of access thereto, an auxiliary housing within said chamber, passages between said chamber and housing, and heating means mounted in said housing and comprising a plurality of electrical resistance bars mounted on insulated lugs.

In testimony whereof I have hereunto signed my name in the presence of two subscribing witnesses.

WILLIAM H. RIPLEY.

Witnesses:

ROBERT W. ASHLEY,
SEABURY C. MASTICK.
